TAPE DISPENSER

Jean Otis Reinecke, Chicago, Ill., assignor to Minnesota Mining & Manufacturing Company,
St. Paul, Minn., a corporation of Delaware

Application January 24, 1952, Serial No. 18,191

Term of patent 14 years

(Cl. D74—1)

To all whom it may concern:

Be it known that I, Jean Otis Reinecke, a citizen of the United States, residing at Chicago, in the county of Cook and State of Illinois, have invented a new, original and ornamental Design for a Tape Dispenser, of which the following is a specification, reference being had to the accompanying drawing, forming a part hereof.

Figures 5 and 6 are front and rear elevations, respectively, thereof.

The dominant features of my design reside in the portions shown by means of full lines in the drawing.

I claim:

The ornamental design for a tape dispenser, as shown and described.

JEAN OTIS REINECKE.
